UNITED STATES PATENT OFFICE

146,723

DESIGN FOR A SHAVING SOAP BOWL
OR THE LIKE

Abraham Levy, New York, N. Y., assignor to Parfum L'Orle, Inc., New York, N. Y., a corporation of New York

Application May 15, 1946, Serial No. 129,721

Term of patent 7 years

(Cl. D86—10)

To all whom it may concern:

Be it known that I, Abraham Levy, a citizen of the United States and a resident of the city, county, and State of New York, have invented a new, original, and ornamental Design for a Shaving Soap Bowl or the like, of which the following is a specification, reference being had to the accompanying drawing, forming part thereof, in which:

Fig. 1 is a front elevational view of a shaving bowl or the like, embodying my design.

Fig. 2 is a rear view of the same.

Fig. 3 is a plan view of the same.

I claim:

The ornamental design for a shaving soap bowl or the like, as shown.

ABRAHAM LEVY.
